INTERNAL COMBUSTION ENGINE

John J. Keough, Hudson, Mass.

Application August 22, 1939, Serial No. 291,409

4 Claims. (Cl. 123—66)

My invention relates to improvements in internal combustion engines, and an important object of my invention is to provide an internal combustion engine combining the advantageous features of two-cycle and four-cycle operation, whereby greater efficiency and power output are obtained considering size and weight of the engine.

Other important objects and advantages of my invention will be apparent from a reading of the following description taken in connection with the drawings wherein for purposes of illustration I have shown a preferred embodiment of my invention.

15 In the drawings:

Figure 1 is a general right hand side elevational view of an embodiment of the present invention.

Figure 2 is an end elevational view of Figure 1 looking from right to left.

Figure 3 is an enlarged transverse vertical sectional view taken through Figure 1 approximately on the line 3—3 and showing the parts in the explosion position.

25 Figure 4 is a view similar to Figure 3 but showing the parts in the exhausting position.

Figure 5 is an enlarged transverse vertical sectional view taken through the piston assembly showing the operative relationship of the parts.

30 Figure 6 is an enlarged top plan view of the cylinder extension.

Figure 7 is a top plan view of the ratchet block or cross-head.

35 Figure 8 is a top plan view of the crankshaft.

Figure 9 is an enlarged bottom plan view of the auxiliary piston.

Figure 10 is an enlarged transverse vertical sectional view taken through Figure 5 approximately on the line 10—10.

40 Referring in detail to the drawings, the numeral 5 generally designates an engine in accordance with the present invention having a suitable number of cylinders 6 which are provided in one side with an exhaust port 7 having a connection 8 with an exhaust manifold 9, an extension 10 being superposed on and connected to the upper end of the cylinder head 11 closing the upper end of the extension 10 and having therein the intake port 12 which is housed by a fitting 13 which has a connection 14 with the intake manifold 15 which has a carburetor coupling 16.

The fitting 13 has a partition 17 with a valve seat opening normally closed by a ball valve 18 55 which is upwardly pressed by a spring 19 resting

on a retainer 20, whereby the fuel mixture will be intaken through the fitting 13 into the top of the cylinder only on a down-stroke of the piston assembly.

The engine further involves a crankcase 21 in which is supported a crankshaft 22 having throws 23 including a crankpin 24.

Working in the cylinder 6 is the main piston 25 which is generally conventional in form and has ring grooves 26 in its upper part and a skirt 27 on its lower part. A piston pin 28 traverses the upper part of the skirt 27 below the head of the piston while the top 29 of the piston has concave side openings 30 and 31 therein in each of which is ground fitted a respective ball 32, 33 15 which is held in place by a plug retainer 34, 35 threaded into the said top 29 of the piston. Through these balls 32 and 33 work ground fitted rods 36 and 37, respectively, the working fit of the balls and of the rods being such as to maintain compression above the piston 25. The upper ends of the rods 36 and 37 are traversed by a pin 38 which traverses depending ears 39 and 40, clearly visible in Figure 10, which depend from a journal 41 which can turn and slide on a piston pin or bar 42, 43, respectively, which are arranged parallel across and in the skirt portion 44 of the auxiliary piston which is generally designated 45 and which has in its head a ring groove 46 for a compression ring. The auxiliary piston 45 works in the cylinder extension 10 and the inner wall of this extension has vertical slots or grooves 47 formed at circumferentially spaced intervals to allow the gas or other fuel to pass from a point above the auxiliary piston 45 to the space which exists between the top of the main piston 25 and the auxiliary piston and thereby relieve back pressure against the piston 45. The extension 10 is provided in a wall with a spark plug opening 48 in which is located a spark plug 49 at a level below the uppermost position of the auxiliary piston as illustrated in Figure 3 of the drawings.

The lower ends of the rods 36 and 37 are pivoted as indicated by the numerals 50 and 51 on respective laterally projecting pins on the ratchet block constituting a cross-head which is designated 52 and which is formed with an opening 53 provided with suitable projections for engaging in the endless reversed worm thread 54 on the worm 55, which is journaled at its upper end as indicated by the numeral 56 in the wrist pin end 57 of the piston assembly and at its lower end as indicated by the numeral 58 in the con-

necting rod bearing 59. The lower part of the thread 54 at the point indicated by the numeral 60 is increased in pitch for a purpose to be hereinafter indicated. The lower part of the worm 55 is provided with a beveled pinion 60 which is meshed with a beveled gear 61 on the crankshaft pin 24, the ratio of the teeth on the two gears being as 3 to 1 for a purpose to be hereinafter indicated.

10 The cross-head 52 is provided in its opposite ends with holes 62 and 63 which slidably receive the rods 64 and 65 which are pinned at their upper ends in sockets in the wrist pin end 57 and at their lower ends in sockets in the upper section 15 of the connecting rod bearing 59. The connecting rod bearing 59 is composed of the upper section 66 and the lower section 67 the sections being assembled by bolts 68.

In a suitable arrangement of the invention the 20 bevel gear 61 is a thirty-six tooth bevel gear and the bevel pinion 60 has twelve teeth, thereby providing a three to one gear ratio. The ratio of these gears must be proportioned to the number of threads per inch on the worm 55. In the 25 present embodiment there is one thread per inch on the worm 55 which causes the cross-head to travel the full length of the worm under one revolution of the beveled pinion 60, thereby establishing the ratio of 3 to 1. The increased thread 30 on the end of the worm 55 is at the end of the stroke of the cross-head and has its operation described further herein. If there were two threads per inch on the worm then the beveled pinion 60 would have to make two full revolutions 35 in order to cause the cross-head to travel the full length or stroke of the worm, thereby requiring the use of a larger beveled gear of 72 teeth and increasing the ratio of these gears to 6 to 1. One third of a revolution of this 72 40 toothed gear would then perform two full revolutions of the beveled pinion 60. So with every change of threads per inch on the worm to meet the requirements and specifications of different sized engines the ratio of the bevels must change 45 accordingly to correspond. No matter what the ratio of the bevels may be the action of the auxiliary piston 45 during the course of the explosion, in intaking and exhausting the gases simultaneously, and compressing the gas, is built 50 around three cycles or three equally divided portions of one complete revolution of the crankshaft 22. One revolution of the crankshaft performs three operations of the auxiliary piston 45 by means of the revolving action of the bevel 55 gears.

In Figure 3, the main piston 25 and the auxiliary piston 45 are at the top of the stroke with the cross-head just above the increased threads at the lower end of the worm 55 as indicated by 60 the numeral 60, beginning to engage in the endless worm thread 54 on the worm 55, and ready to fire, and when the spark plug 49 is energized the explosion occurs between the auxiliary piston and the main piston, thereby forcing the main 65 piston downwardly on the power stroke and turning the crankshaft counterclockwise a distance of one third of a revolution of the crankshaft or to a position 120 degrees from the top position. The auxiliary piston remains in the top position shown 70 in Figure 3, because the bevel gear 61 is turned one-third of a revolution, causing the beveled pinion 60 to make one complete revolution and turn the worm 55 with it so as to seemingly drive the cross-head 52 upwardly, thereby forcing the auxiliary piston 45 upwardly. Actually the 75

auxiliary piston does not move relative to the cylinder head but the worm moves downwardly being a part of the main piston assembly turning as it does, thereby forcing the auxiliary piston away from the main piston and giving the auxiliary piston 45 a stationary position in the cylinder extension during the course of the explosion. This completes the first of the three cycles of operation.

Still under the compulsion of the exploded 10 charge the main piston moves into the second cycle of operation from the 120 degree crankshaft position as shown in dotted lines in Figure 3 to a 240 degree crankshaft position as shown in dotted 15 lines in Figure 4 in achieving which the crankshaft has turned another one third of a revolution or two thirds of a revolution in all, thereby completing two cycles of operation; during this performance the bevel gear 61 causes another 20 complete (or more) revolution of the beveled pinion 60. The cross-head 52 having reached the top of the worm 55 now starts downwardly thereon because the lugs inside the cross-head opening 53 work across the thread at the top of the worm and follow the course of the reversing thread portion 25 downwardly so as to pull the auxiliary piston 45 downwardly and thereby cause a suction above the auxiliary piston which draws the gas or other fuel through the intake valve at the top of the cylinder head. At the same time the downward 30 movement of the piston 45 forces the burned gas below the auxiliary piston out through the exhaust port 7 below which the main piston 25 is then positioned. This is the end of the second 35 of the three cycles of operation and can be termed the simultaneous intaking and exhausting cycle or stroke. At this point the main and auxiliary pistons are close together again as shown in dotted lines in Figure 4.

From the last described crankshaft position 40 of 240 degrees the main piston 25 moves upwardly toward its original top position thereby completing the final cycle. Figure 3 of the drawings shows the positions of the parts at the end of the third cycle and at the beginning of the first cycle. 45 The final cycle completes the final one-third revolution of the crankshaft causing the beveled gear 61 to effect the final one complete revolution of the beveled pinion 60. The cross-head 52 is at this point at the bottom part of the worm at 50 the top of the numeral 60 at the end of the second cycle and at the beginning of the third cycle, but during the third cycle the ratchet travels upwardly together with the main piston 25 because the increased number of threads at 55 the lower end of the worm 55 as indicated by the numeral 60 permit the cross-head 52 to remain substantially motionless on this upward movement of the main piston 25. There is only a slight movement of the cross-head 52 upwardly 60 during the course of its travel along the increased thread 60. Thus, while the main and auxiliary pistons are moving upwardly together on the last cycle the auxiliary piston moves slightly ahead of the main piston 25 just enough 65 to provide for sufficient space between the main and auxiliary pistons for the exploding charge by the time it completes the last cycle. The increased number of threads 60 must also be proportioned to the ratio of the bevelled gears 60 70 and 61, but in the present embodiment one-half a thread per one-eighth of an inch is necessary, the length of the increased thread being approximately one-eighth of an inch. This makes the length of the entire worm 55 one and one-eighth 75

inches, combining the length of both threads. By one-half a thread is meant that the thread is on just one side of the worm 55 at 60 working downwardly, the other half of the thread being 5 on the opposite side of the worm 55 at 60 working upwardly. While the auxiliary and the main piston are traveling upwardly together the cross-head 52 is working downwardly one-eighth of an 10 inch due to the half thread on one side and upwardly again when it follows the other half of the thread on the opposite side due to the lugs in the cross-head 52 working into the reverse portion of the endless thread 54 at 60. The cross-head 52 will move down and up at 60 with 15 the full revolution of the bevel pinion 60 because the cross-head 52 moves down on the half thread at 60 with one-sixth of a revolution of the beveled gear 61 and up again at the last one-sixth of the revolution of the beveled gear 20 61. The two-sixth revolution is involved in the full final third revolution of the beveled gear 61 and the crankshaft, thereby completing the final revolution of the beveled pinion 60.

One-half thread per one-eighth of an inch 25 equalling four threads per inch, conforms to the 3 to 1 ratio of the bevel gears 60 and 61. The slight rise of the auxiliary piston 45 above the main piston during the last cycle equals the one-eighth inch length of the thread at 60 and the 30 space thus created between the auxiliary and the main piston at the end of the third cycle is where the explosion occurs in the next or first cycle.

On this upward movement of the auxiliary piston 45 in this third cycle it compresses above it a fresh charge of fuel so as to achieve the proper compression of the charge independently 35 of the main piston. When the auxiliary piston reaches the top of its stroke in this compressing 40 action, it passes up through the cylinder extension 10 and forces the compressed gas to pass downwardly through the slots 47 and enter the space between the top of the main piston 25 and the auxiliary piston 45, whereat the charge is 45 ready to be exploded by operation of the spark 49 and the consequent repetition of the cycle described above.

Mathematical formula for finding ratio of beveled gears with a determined number of threads

50 Number of threads $\times$ number of cycles = unknown quantity
to 1

1	$\times$	3	= 3 to 1 ratio
2	$\times$	3	= 6 to 1 ratio
3	$\times$	3	= 9 to 1 ratio
55	$\times$	3	= 4½ to 1 ratio

Operation of auxiliary rods and parts

During the first cycle the ground rods 36 and 37 have sidewise movement only, caused by the 55 throw of the crankshaft while the ball-bearing fittings slide down the rods 36 and 37. The depending ears 39 and 40 swing from left to right and slide the journals 41 from left to right on the piston pin or bar 42 and 43 respectively.

60 In the second cycle the rods 36 and 37 slide downwardly through the ball-bearings 32 and 33 with the depending ears and journals swinging

and sliding from right to left. The rods 36 and 37 are substantially motionless in the balls 32 and 33 except for the slight movement upwardly and downwardly during the action of the cross head 52 on the thread at 60.

5 By the means described the economy and simplicity of action of the two cycle type of engine are merged with the power advantages of the four cycle type of internal combustion engine.

10 Although I have shown and described herein a preferred embodiment of my invention, it is to be definitely understood that I do not desire to limit the application of my invention thereto, except as required by the scope of the subjoined 15 claims.

1f Having described the invention, what is claimed as new is:

1. An internal combustion engine comprising a cylinder, a piston assembly working in said cylinder, a crankshaft including a throw and a 20 crankpin, said piston assembly comprising a main piston and an auxiliary piston above said main piston, a connecting rod assembly operatively connecting said main and auxiliary pistons to said crankpin, said connecting rod assembly including positioning means for operating said auxiliary piston relative to said main piston, said positioning means comprising a rotary reversing worm 25 operatively connected to said main and auxiliary pistons, and gear means operatively connecting said worm and said crankpin.

2. In an internal combustion engine, a cylinder, a crank shaft including a revolving throw, a pair of main and auxiliary pistons, respectively, in said cylinder differentially positionable 35 relatively, a piston rod assembly operatively connecting the main piston to said throw, and means to position said auxiliary piston differentially comprising a worm drive operative under revolving movement of said throw.

3. In an internal combustion engine, a cylinder, a crank shaft including a revolving throw, a pair of main and auxiliary pistons, respectively, in said cylinder differentially positionable relatively, a piston rod assembly operatively connecting said main piston to said throw, and means to position said auxiliary piston differentially comprising a cross head slidably mounted on said assembly and operatively connected to said auxiliary piston, and a reversing worm drive for 50 operating said cross head operative under revolving movement of said throw.

4. In an internal combustion engine, a cylinder, a crank shaft including a revolving throw, a pair of main and auxiliary pistons, respectively, in said cylinder differentially positionable relatively, a piston rod assembly operatively connecting the main piston to said throw, and means to position said auxiliary piston differentially comprising a cross head slidably mounted on said assembly, a pair of auxiliary piston rods slidably and pivotally extended through said main piston, and operatively connecting said cross head to said auxiliary piston, and a reversing worm drive for 55 said cross head operative under revolving 60 movement of said throw.

65 JOHN J. KEOUGH.
